SASH MOUNTING

Charles H. Talbot and Andrew Peters, Cos Cob,
Conn.

Application May 31, 1935, Serial No. 24,344

10 Claims. (Cl. 16—160)

This invention relates to a swinging sash mounting. More especially, our invention relates to a sash of the type which is adapted for first a vertical movement, and then a horizontal 5 swinging movement to an open position.

The invention is of especial utility in connection with interlocking sash of various types, both wood and metal, in which the relation of the sash to the frame is such that portions of each are 10 interlocked to contribute a weatherstripping effect. Thus, the sash in itself, by its relation to the frame, obviates the need of weatherstripping because the window sash and the frame are in the same relation as usual commercial weatherstripping.

In a structure of this type, in order to swing the sash horizontally relatively to the frame from a closed to an open position, it is necessary to move it vertically first to release the sash from 20 interlocking relationship with the frame, after which the sash may swing freely. Fixtures and hinges of many types have been developed in the art for this sort of structure, but none of these have achieved any real commercial success.

25 While the combination which we shall disclose hereinafter is not broadly novel, since lifting and swinging sash mountings are old, yet it discloses a relatively broad improvement to the art, which art is of course confined to a very limited field.

30 As is frequently the case in inventions developed in a very narrow and highly developed field, a contribution which is seemingly of narrow scope really contributes to the art, many times, a relatively basic improvement, which is the last step 35 toward the proper development of a commercial structure. We believe our contribution to be of this nature.

Before referring to the drawing for a detailed description of our invention, we should like to 40 indicate generally some of the major improvements which we feel are embodied in our invention.

In general, our invention comprises the mounting of a window sash on a movable hinge portion 45 adapted to move vertically, and then to rotate relatively to a fixed hinge portion. The movable hinge portion has preferably an extension on which is pivoted a handle having a cam portion bearing on the pin of the hinge, which pin is 50 preferably fixed to the fixed hinge portion. The handle is so mounted, preferably, that when it is swung upwardly in the same direction in which the window sash is to be moved, its cam portion bearing on the pin will impart lifting movement 55 to the window sash in the axis of the hinge pin.

We feel that the movement of the window sash through effort applied in the axis of the hinge pin, and this in further combination with a lever adapted to be moved in the direction of the lifting of the window sash, is quite an important 5 contribution.

Preferably, the fixed hinge pin of our invention is of considerable length relative to the movable hinge portion, which is in the form of a thin disk. Thus, the movable hinge portion always has full bearing on the hinge pin, which is in itself of considerable importance. Also, any friction which may be developed between the disk and the hinge pin will be relatively slight because of the small bearing area between the 15 hinge pin and the movable hinge portion. These features, we might indicate, are also of relatively great importance in this highly developed art.

A further feature of our invention resides in the use of the lifting lever handle for locking 20 the casement in a closed position or in a partially open position. Thus, the handle carries a lug which is adapted to rest in any one of a series of detent slots on the fixed hinge portion of our assembly. Movement of the handle in a 25 direction to lift the window sash will first release the window sash and its movable hinge portion relatively to the fixed hinge portion, and this releasing will take place while the window sash is being elevated for release from its interlocking 30 weatherstripping association with the frame. Thereafter, the window sash may be rotated on the fixed hinge pin to a predetermined open position, and then lowered while the handle lug enters one of the detent slots for locking the 35 sash in said predetermined open position.

Having thus described generally our invention, we shall now refer to the drawing and will describe a detailed embodiment of the invention.

In the drawing, Fig. 1 is a front view of a pair 40 of swinging window sashes embodying my invention and showing one sash in a raised position and ready to be rotated. Fig. 2 is a section taken along line 2—2 of Fig. 1, and illustrates the interlocking relation between the two window 45 sashes. Fig. 3 is a section taken along line 3—3 of Fig. 1. Fig. 4 is an elevation and partial section of my lower hinge and the handle used therewith.

Referring now more particularly to the drawing, it should first be indicated that the casements illustrated are of the structural steel type, although it is possible to utilize the invention where other materials, such as wood, are preferred. Each swinging window sash is mount- 50 55

ed in interlocking relation to the frame 2, as is probably best illustrated in Figs. 2 and 3. Fig. 2 shows the relationship between the left and right hand casement window sashes whereby the 5 two are interlocked. In Fig. 3 the vertical interlocking of a sash 1 with its frame 2 is best illustrated. Each sash 1 has an upper hinge and a lower hinge supporting the same for vertical and horizontal movement relatively to the frame 2. 10 The hinges are naturally arranged so that each sash may first be raised to release it from interlocking engagement with its frame 2 and then rotated to a particular open position.

The upper hinge as illustrated in Fig. 3, comprises a movable hinge portion 5 secured to the movable sash, and a fixed hinge portion 6 secured to the frame 2. The fixed pin 7 is carried by the fixed hinge portion 6, and a nut 8 screw threaded on this pin limits the upward movement of the hinge portion 5, and therefore of the sash 1 relatively to the frame.

The lower hinge is shown in Figs. 2, 3, and 4, and comprises a fixed hinge portion 10 secured to the frame 2, and having a fixed hinge pin 11 secured thereto. The fixed hinge portion 10 also has a series of detent slots 14, the use of which will be explained presently. Mounted on the fixed hinge pin 11 is a disk 9 constituting the movable hinge portion, and adapted to be secured to the movable sash 1 for movement integrally therewith vertically relatively to the pin 11, and also for rotation about the pin 11.

Integral with the disk 9 is an extension on which is pivoted, through means of a pin 12, a 35 lever handle 13 having a cam portion 13a in enclosing relation to the pin 11. The cam portion 13 has a cam surface 13b in camming relation to pin 11, so that as the lever handle is swung upwardly from its position in Fig. 4, the cam surface 13b will cooperate with the pin 11 to raise the disk 9 on the pin 11, and thus elevate the sash 1 relatively to the frame 2 to the position of Fig. 1. This lifting will of course be imparted in the axis of the pin 11, and it will be effected by movement of the handle 13 in the direction of the lifting of the window frame 1, as will be readily appreciated. This not only facilitates the lifting of the relatively heavy sash, but applies the lifting effort in a manner so as not 50 to bind the hinges.

A locking lug 15 on the lever handle 13 is co-operable with the detent slots 14 of the lower hinge portion 10, as shown in Fig. 4, to prevent rotation of the sash about the hinge pin 11, and 55 this relation of the lug 15 to the detent slots 14 is adapted to hold the window sash in any rotated position, as will be clearly understood by those skilled in the art. Also, for locking the window, the lever handle 13 may be equipped 60 with an opening 16 co-operable with the opening 18 of a lug 17 carried by the window sash for securing the handle through means of a fastener, such as a padlock shackle.

We believe that the construction of our invention will now be apparent to those skilled in the art, and that its operation will be readily understood. While we have described a particular form of our invention, we wish to reiterate, that we consider this improvement to be broad within 70 a narrow field, and we feel ourselves entitled to relatively broad claims, and to a relatively broad interpretation of those claims.

We claim:

1. In a device of the class described and 75 adapted for use on a window sash mounted for

vertical and swinging movement relatively to a frame, a fixed hinge portion fixed to the frame, a hinge pivot pin, a movable hinge portion slidably mounted on said pin for movement into a lowered and a raised position and freely rotatable in either position, said movable hinge portion and window sash being rotatable together, a lever handle pivoted to said movable hinge portion and having a cam portion bearing on said hinge pivot pin, whereby rotation of said handle on its pivot will cause said cam to raise said window sash axially relatively to said pin, said movable hinge and said sash being rotatable thereafter by said handle, and means whereby said handle locks said sash against 15 swinging movement when said handle is in its horizontally extending position.

2. In a device of the class described and adapted for use on a window sash mounted for vertical and swinging movement relatively to a frame, a fixed hinge portion fixed to the frame and having a fixed hinge pivot pin, a movable hinge portion slidably and rotatably mounted on said pin and secured for movement with the window sash, a lever handle pivoted to said movable hinge portion and having a cam portion bearing on said hinge pivot pin, whereby rotation of said handle on its pivot will cause said cam to raise said window sash axially relatively to said pin, said movable hinge and said sash being rotatable thereafter by said handle, and means whereby said handle locks said movable hinge portion 30 against rotation when said handle is in a position corresponding to a lowered position of said movable hinge portion.

3. In a device of the class described and adapted for use on a window sash mounted for vertical and swinging movement relatively to a frame, a fixed hinge portion fixed to the frame and having a fixed hinge pivot pin, a movable hinge portion 40 slidably and rotatably mounted on said pin and secured for movement with the window sash, a lever handle pivoted to said movable hinge portion and having a cam portion bearing on said hinge pivot pin, a locking lug on said handle, said fixed hinge portion having a series of detent slots into one of which said lug enters to lock said sash against rotation, movement of said handle on its pivot relatively to the movable hinge portion being effective to release said lug from one of said 50 detent slots and simultaneously raise said sash axially relatively to said fixed hinge pin, said movable hinge portion and said sash being rotatable thereafter by said handle.

4. In a device of the class described and adapted for use on a window sash mounted for vertical and swinging movement relatively to a frame, a fixed hinge portion fixed to the frame and having a fixed hinge pivot pin, a movable hinge portion 60 slidably mounted on said pin for movement into a lowered and a raised position and freely rotatable in either position, said movable hinge portion and window sash being rotatable together, a lever handle pivoted to said movable hinge portion and having a cam portion bearing on said hinge pivot pin and in covering relation thereto, whereby rotation of said handle on its pivot will cause said cam to raise said window sash axially relatively to said pin, said movable hinge and said sash being 70 rotatable thereafter by said handle.

5. In a device of the class described and adapted for use on a window sash mounted for vertical and swinging movement relatively to a frame, a fixed hinge portion fixed to the frame and having 75

a fixed hinge pivot pin, a movable hinge portion slidably and rotatably mounted on said pin and secured for movement with the window sash, a lever handle and means pivoting said handle on said movable hinge portion, a cam portion on said handle bearing downwardly on said fixed hinge pin, whereby upward swinging of said lever handle on its pivot in the direction of the lifting of said window sash will cause said cam to impart upward movement to said sash in the axis of said fixed hinge pin, and means on said handle engageable with means on said fixed hinge when said lever handle and movable hinge portion are in their lowered position, whereby to lock said movable hinge portion against rotation.

6. In a device of the class described and adapted for use on a window sash mounted for vertical and swinging movement relatively to a frame, a fixed hinge portion fixed to the frame and having a fixed hinge pivot pin, a movable hinge portion slidably and rotatably mounted on said pin and secured for movement with the window sash, said movable hinge portion being in the form of a disk with an extension, a lever handle, means pivoting said handle on said movable hinge portion extension, said handle having a cam portion bearing downwardly on said fixed hinge pin, whereby upward swinging of said lever handle on its pivot in the direction of the lifting of said window sash will cause said cam to impart upward movement to said sash in the axis of said fixed hinge pin.

7. In a device of the class described and adapted for use on a window sash mounted for vertical and swinging movement relatively to a frame, a fixed hinge portion fixed to the frame on the inside of said sash, a hinge pivot pin, a movable hinge portion slidably and rotatably mounted on said pin and secured for movement with the window sash, a horizontally extending lever handle pivoted to said movable hinge portion and having a cam portion bearing on said hinge pivot pin, said cam portion being so designed that rotation of said handle on its pivot in the direction of the elevation of said window will cause said cam to raise said window sash axially relatively to said pin, said movable hinge and said sash being rotatable thereafter by said handle, and means whereby said handle locks said sash against swinging

movement when said handle is in its horizontally extending position.

8. In the combination of claim 3, means for locking said lever handle with its lug in one of the detent slots.

9. In a device of the class described and adapted for use on a window sash mounted for vertical and swinging movement relatively to a frame, a fixed hinge portion fixed to the frame and having a fixed hinge pivot pin, a movable hinge portion slidably mounted on said pin for movement into a lowered and a raised position and freely rotatable in either position, said movable hinge portion and window sash being rotatable together, a lever handle pivoted to said movable hinge portion and having a cam portion bearing on said hinge pivot pin, a locking lug on said handle, said fixed hinge portion having a series of detent slots into one of which said lug enters to lock said sash against rotation, movement of said handle on its pivot relatively to the movable hinge portion being effective to release said lug from one of said detent slots and simultaneously raise said sash axially relatively to said fixed hinge pin, said movable hinge portion and said sash being rotatable thereafter by said handle.

10. In a device of the class described and adapted for use on a window sash mounted for vertical and swinging movement relatively to a frame, a fixed hinge portion fixed to the frame and having a fixed hinge pivot pin, a movable hinge portion slidably mounted on said pin for movement into a lowered and a raised position and freely rotatable in either position, said movable hinge portion and window sash being rotatable together, a lever handle pivoted to said movable hinge portion and having a cam portion bearing on said hinge pivot pin and in covering relation thereto, whereby rotation of said handle on its pivot will cause said cam to raise said window sash axially relatively to said pin, said movable hinge and said sash being rotatable thereafter by said handle, and means whereby said handle locks said movable hinge portion against rotation when said handle is in a position corresponding to a lowered position of said movable hinge portion.
